UNITED STATES PATENT OFFICE

2,485,443

SEAT CUSHION

Edward R. Hathaway, Detroit, Mich., assignor to
 Briggs Manufacturing Company, Detroit, Mich.,
 a corporation of Michigan

Application February 8, 1945, Serial No. 576,743

3 Claims. (Cl. 155—179)

1

This invention relates to springs generally useful in the fabrication of the upholstered seat cushions and backs of seat structures, the invention relating particularly to improvements in the construction of so-called flat type wire springs of sinuous or zig-zag formation.

An object of the invention is to provide a spring structure made up of a series of parallel rows of spring members each having an improved zig-zag formation adapted to have a greater effective range of deflection under load.

A further object of the invention is to provide a spring of generally zig-zag construction formed from a length of wire bent into a series of alternate loops in such manner as to improve the resiliency of the structure and provide progressively increasing resistance to load over a wider deflection range than possible with flat-type sinuous springs heretofore used.

Other objects of this invention will appear in the following description and appended claims, reference being had to the accompanying drawings forming a part of this specification wherein like reference characters designate corresponding parts in the several views.

Fig. 1 is a plan view of a spring structure embodying spring members constructed in accordance with the present invention.

Fig. 2 is a section taken substantially through lines 2—2 of Fig. 1 looking in the direction of the arrows.

Fig. 3 is an enlarged fragmentary view of a portion of one of the spring members.

Figs. 4 and 5 are graphs illustrating comparative tests made, respectively, of a spring member embodying the present invention and a sinuous flat type spring member of conventional type.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there is illustrated, by way of example, one embodiment of the invention adapted to be utilized in the fabrication of an upholstered seat or back structure. Any suitable supporting frame or mounting may be employed in the spring assembly such as a rectangular metal frame illustrated in the drawings comprising spaced side members 10 connected at their

ends by end members 11. Extending transversely between and spanning the side frame members 10 are a series of individual spring members 12 spaced equal distances apart and arranged in parallelism. Each spring member 12 is formed from a single length of steel wire of suitable gage which is bent into a zig-zag formation having alternate loops 13 and 14 all lying in the same plane when the spring is in flat condition before installation in the frame. The springs before assembly are pre-set so that when mounted in the frame they assume under tension an outwardly, or upwardly as the case may be, bowed or curved position as shown in Fig. 2. The ends of each spring member may be anchored in any suitable manner such as by inserting the ends into channels formed by the members 10, the sides of which are crimped together to clamp the ends of the spring tightly in position.

The alternating loops 13 and 14 of each spring member are each preferably formed into substantially identical general elliptical shape and are nested together so that substantial end areas of each loop overlap or lie opposite to equivalent areas of two adjacent opposed loops. Thus, as clearly illustrated in Fig. 1, the formation of the alternating loops provides in effect two rows of loops in the longitudinal direction of the spring.

As shown particularly in Fig. 3 each loop 13 and 14 is formed and arranged so that its length measured longitudinally of the spring is materially greater than its width measured in a transverse direction. Thus, the length of the loop measured through the major axis thereof is represented by the distance x and the width of the loop measured through the minor axis thereof is represented by the distance y . In the present embodiment herein selected for the purposes of illustration, the distance x is approximately twice the distance y , the latter corresponding to approximately one-half the entire width of the spring member. With this construction the length of each loop corresponds approximately to the width of the spring member. The adjacent loops 13 or 14 are preferably arranged in close relationship with the distance w between each adjacent pair being much less than the length of the loop, such as approximately one-fifth the distance x . Furthermore, it will be noted that this construction provides a very closely nested arrangement of the alternating loops in which the centers thereof lie on a zig-zag line as indicated by the dotted line z in Fig. 3. It will be understood that the shape and size of the loops as well as the dimensional proportions given above may vary within the

scope of the invention without departing from the spirit thereof.

With the alternating loops 13 and 14 arranged in nested relation with their major axes extending longitudinally of the spring instead of transversely as heretofore it has been found by comparative tests that the present spring will sustain much greater loads without collapse than flat-type sinuous springs heretofore used. In Fig. 4 there is illustrated graphically the deflection rate of a spring constructed in accordance with the present invention as compared with a conventional spring of sinuous construction having a deflection rate illustrated graphically in Fig. 5. This conventional spring had elongate transversely extending relatively narrow U-shaped loops with substantially parallel sides, this construction being common in the prior art. The comparative tests were made with springs formed with the same gage steel wire and were in all respects conducted so that reliable comparisons were reached. In each instance the spring member tested was mounted in bowed or arched manner, as illustrated in Fig. 2, the crown of the spring at the highest point being two inches above a horizontal plane extending through the ends of the spring. In the graph illustrated in Fig. 4, depicting the tests conducted on a spring member substantially as illustrated in the drawings, the deflection rate is shown by the curve or graph line 15 extending through a series of points determined by measuring in inches successive increments of downward deflection of the spring produced by successive loads, measured in pounds, placed on the spring. It will be noted from this graph that the spring deflection progressively increased as the load increased, and that the spring resistance had a magnitude of twenty-seven pounds when a deflection of four inches was reached. Referring to the graph illustrated in Fig. 5, depicting the tests made with a conventional flat spring, the maximum effective resistance of the spring was reached at a deflection of two and three-fourths inches under a load of eighteen pounds, as shown by the curve or graph line 16. From this point the spring started to collapse and the effective resistance of the spring with a four inch deflection was but slightly over eleven pounds.

Thus, it will be seen that the present improved spring possesses a considerably greater effective deflection range than flat springs of conventional type and is capable not only of sustaining progressively increasing loads throughout this range but materially greater loads than heretofore possible with conventional flat-type sinuous springs.

I claim:

1. In a seat structure or the like having a frame, a plurality of flat-type spring members normally bowed upwardly from a substantially horizontal plane and being arranged on said frame in curvilinear alignment, each of said spring members comprising a length of wire formed to provide alternating reversely bent loops extending transversely of the spring member, the distance between the closed ends of each loop measured longitudinally of the spring member being greater than the width of the loop measured transversely from the outer edge of the loop to an imaginary line running lengthwise of the spring member at the middle thereof from side to side.
  - 10 2. In a seat structure or the like having a frame, a plurality of flat-type spring members normally bowed upwardly from a substantially horizontal plane and being arranged on said frame in curvilinear alignment, each of said spring members comprising a length of wire formed to provide alternating reversely bent loops extending transversely of the spring member, the distance between the closed ends of each loop measured longitudinally of the spring member being approximately as great as the width of the spring member.
  - 15 3. In a seat structure or the like having a frame, a plurality of flat-type spring members normally bowed upwardly from a substantially horizontally plane and being arranged on said frame in curvilinear alignment, each of said spring members comprising a length of wire formed to provide alternating reversely bent elliptically shaped loops extending transversely of the spring member, the major axis of each loop extending longitudinally of the spring member and approximating the width of the latter, and the width of the opening between the ends of adjacent loops being less than half of the length
  - 20 40 of said major axis.

EDWARD R. HATHAWAY.
